UNITED STATES PATENT OFFICE.

HENRY J. SCHLACKS, OF CHICAGO, ILLINOIS.

ILLUMINATING MEANS.

1,241,031.

Specification of Letters Patent. Patented Sept. 25, 1917.

Substitute for application Serial No. 857,788, filed August 20, 1914. This application filed February 14, 1916. Serial No. 78,300.

To all whom it may concern:

Be it known that I, HENRY J. SCHLACKS, citizen of the United States, residing at Chicago, in the county of Cook and State of Illinois, have invented certain new and useful Improvements in Illuminating Means; and I do hereby declare the following to be a full, clear, and exact description of the invention, such as will enable others skilled in the art to which it appertains to make and use the same.

This invention relates to improvements in artificial illuminating means for auditoriums, and is particularly intended and designed for the illumination of basilica churches, though it may obviously be adapted to auditoriums of other styles of architecture, and more particularly high-ceilinged auditoriums.

The main object of the invention is to provide a system of artificial illumination which will harmonize with the architectural effects of the auditorium, and will not interfere with the purposes and intent of the style of architecture thereof and will, at the same time, provide illumination of both the direct and indirect type which will bring out all of the architectural and decorative beauties of the auditorium at a minimum cost of power consumption, and without producing a glaring light which will be annoying to the eyes of the occupants of the auditorium.

Having in mind particularly the basilica church auditorium such as is shown in the accompanying drawings, it is believed that a few words of explanation will aid a complete and full understanding of the invention.

In plan, the basilica comprises a rectangular nave or auditorium, in length from two to three times its breadth, the chief entrance at one end and at the opposite extremity the semi-circular apse where originally sat the Roman pretor and which place later became the Christian sanctuary. The nave is flanked with colonnades in two stories. In the upper or clearstory the side walls are close to or attached to the columns and perforated between with window openings. On the lower level the walls are separated from the colonnade by the side aisles. These aisles are vaulted over, directly above them is the triforium gallery with arcade openings into the main auditorium. This tri-

forium may form a gallery of considerable size, it is more often reduced to a vacant tympanum chamber under the side roofs and directly over the vaults of the side aisles. Then, in place of the arcade openings, a series of ornamental recesses is set into the wall or a frieze or cornice is used to decorate the otherwise vacant wall space. The chief purpose, however, of this ornamentation of the side walls just above the arches of the lower columns is to add to the scale of the perspective.

Many variations from the above plan, such as the duplication of the side aisles, an apse at both ends, or the entire absence of these features and usually the addition of a transept in front of the sanctuary, suggesting in the plan the form of a cross, have been introduced by the accidents of position or the exigencies of the ritual. The ceiling may be arched, vaulted, or flat and the upper columns are often mere conventions. These variations in the general design do not affect the problem of artificial illumination, a problem common to all buildings of this type.

The basilica design is well and naturally adapted to daylight illumination but presents serious difficulties in respect to artificial lighting. In its original applications when the building was used as a shrine or a forum there was no need for night illumination and, except for purely ceremonial purposes, no need for artificial lights. Later when used as a place of assembly it became necessary to add seating arrangements to the structure and means for lighting independent of the sunlight. The problem of providing these means is complicated by the great height of the ceiling and the architectural requirements. The majesty and simplicity of the basilica call for a clear open space free from extraneous, hanging devices which tend to reduce the scale and mar the dignity and grandeur of the design.

The common use of the chandelier in basilica churches resulted from the fact that it was the only fixture to which the available lighting units, candles, burners, or the carbon incandescent lamp could be readily adapted. Objections to the chandelier system are many and varied. The quality of illumination is poor because of the uneven

distribution from concentrated sources. The eyes of the audience are subject to a maximum of glare and, where it is most needed, a minimum of illumination. When placed in the best position for the nave lighting the fixture usually hangs in a direct line of the choir gallery and sanctuary. At all times it obstructs the view of the organist and the gallery audience looking toward the altar and at night, interposes in the very center of their field of vision glaring lights in addition. The chandelier is expensive to operate because much of the light generated is wasted. The efficiency is lower than it might be were it not for artistic considerations which generally prevent the use of reflecting glassware and the selection of lamps on the basis of efficiency rather than appearance. A large number of outlets and lamps are needed and these, on account of their exposed position, and inaccessibility, are expensive to keep clean. Chandeliers should be thoroughly cleaned at least twice yearly and the metal parts periodically polished and lacquered. This work is commonly neglected and consequently the depreciation is high. However, the fixture is liable to become obsolete before the useful life is completed, due to advances in the art and changes in the style of lamps. On account of its conspicuous position, the chandelier must be richly ornamented and thus it is high in first cost. Finally, as a fixture it is out of place in the architectural principle of the basilican design.

The user of an electric lighting system invests a sum of money for which is obtained a value received in light. The sums expended depend upon the number of lamps used and the hours of burning; but the light depends upon the condition of the lamps. Two factors make this condition: age and blackening of the lamp is one—it pays to discard the lamps at the first sign of blackening rather than use them until they burn out—and the other factor is dirt. All lighting systems, with the single exception of an open flame, have their highest efficiency when new and clean and thereafter suffer a constantly decreasing efficiency with accumulations of dust films on the glass which transmits or reflects the light. This dust obstructs from 10 to 50 per cent. of the light generated, and a corresponding waste forms a part of the electric bill. Providing the apparatus is relatively accessible, the cost of labor for cleaning is a small fraction of the saving. It does not follow that the lighting bills will be lowered by cleaning of the lamps, but the saving appears in the form of more light. Or, if it is found that a dirty lamp will give sufficient light it will be economy to put a smaller clean lamp in its place. If this policy is carried out the saving will then appear directly in the

operating costs. Proper cleaning of lighting equipment in churches is commonly neglected, partly because the economics of the matter are little understood and partly because the labor of cleaning is greater than it should be. The matter should not be viewed from the standpoint of ordinary cleanliness but rather as a means for cutting down operating expenses. Lighting equipment should be designed for the best possible protection from dust and for easy access to clean and renew the lamps.

Of the various systems in use, the purely indirect lighting system probably suffers the most from dust. The upwardly directed reflectors and lamps are in the best position to receive falling dust. Further, their location is usually awkward and often dangerous to reach. The efficiency of this system is low at its best and the affinity for dust accumulations seriously impairs its usefulness. The lamps of a chandelier are exposed to dust especially when frosted lamps are used the roughened surfaces of which retain dirt with tenacity. The trouble of access to the lamps is such as to discourage proper attention.

Accordingly the objects of the present invention are to produce an artificial illumination which shall be soft and devoid of glare, and in which good diffusion and the absence of annoying shadows and reflections are produced. Further, to provide a light of uniform intensity on the reading plane and in which the color of light is appropriate to the general interior color scheme of the auditorium.

Further objects are, to provide a lighting system which will not require skilled labor for its operation and maintenance, and which shall require the minimum expenditure of labor for cleaning and renewal of lamps, and easy accessibility for these purposes. Further, to provide lighting fixtures in which the lamps are protected from dust whereby to maintain maximum efficiency, and in which, by reason of the maintenance of this efficiency, the power consumption for the production of the light is much lower than the present or ordinary standards.

Further objects are to provide illuminating means which shall be mechanically durable and have a minimum or total absence of parts adapted to wear out, and which are protected against corrosion, heat and fire hazard.

The invention consists in the features of construction and combinations of parts whereby the foregoing objects are attained as fully described and claimed in the following specification.

In the accompanying drawings, illustrating the preferred embodiment of the invention;

Figure —1— is a vertical section of a

church building equipped with illuminating means embodying my invention.

Fig. —2— is a fragmentary detail vertical longitudinal section of the same.

Fig. —3— is a fragmentary detail vertical cross-section through the illuminating means embodying my invention.

Fig. —4— is a diagrammatic view showing the electric circuits employed.

My illuminating means comprises preferably linear sources of light disposed along the walls of an auditorium at a suitable point between the floor and ceiling of the latter, and preferably, where possible, at such height from the floor as will make the elevation of the sources of light substantially equal to the distance separating oppositely disposed linear rows. This, of course, will be changed and varied according to the height of the auditorium in proportion of the width thereof. This relation of elevation to width causes both the parallel sources of light to so distribute their rays as to illuminate with substantially equal intensity all of the floor space interposed therebetween, and at the same time such elevation of the illuminating means throws the same entirely out of the normal direction of vision of the occupants of the auditorium, thus relieving the glare which is very discomforting and annoying to the eye.

However, the invention does not reside merely in the aforesaid relative positions of the sources of light, but also in the construction of the housing and distributing means as hereinafter more fully described.

In the accompanying drawings illustrating the preferred embodiment of the invention it will be noted that the side walls A of the auditorium are equipped at a suitable elevation from the floor with cornices B. Each of the latter comprises a base portion C which is directly mounted upon the wall A and the outer portion B, which is suspended from the wall by means of suitable brackets D secured to the wall A and to the upper portion of the cornice B. Thus between the wall A and the member B of the cornice there is a hollow space of ample cross-sectional area which is further bordered by the portion C of the cornice and the brackets D. The illuminating elements are adapted to be contained in this apse. The lower edge of the member B of the cornice is separated from the outer edge of the member C by a free space of a considerable width, this being closed by means of hinged members E carrying ground concavo-convex glass sections F constituting light-diffusing elements for the rays originating from the incandescent lamps G mounted in the space behind the cornice member B, and supported by the latter. Secured to the rear face of the cornice member B is a strip H of a suitable material to which a portion of the housing

for the lamps is secured, said housing comprising a duct K adapted to contain the wires or conduits from which the lamps G are fed, and in the outer wall J of which the sockets K for said lamps are secured, the latter projecting into the main portion L of said housing which contains the said lamps G and the reflector M associated therewith for concentrating the rays upon the diffusing elements F. The front wall of the main portion of the housing L is also secured to the lower end portion of the cornice member B, the latter being equipped with a strip N of sheet metal having a flange O upon which the edges of the members F are adapted to rest when in their normal position, as shown in full lines in Fig. —3—.

The said housing L is preferably made of sheet metal, and is equipped with doors P which may be of any desired design, and either hinged, mounted to slide in guides, or may be bodily removable to provide openings through which to permit the swinging back of the hinged members E, as shown in dotted lines in Fig. —3—, for cleaning their convex faces, and through which access may also be had to the lamps G and their reflectors for purposes of replacement and repair. The top wall of the portion I of the housing is also preferably provided at intervals with hinged doors which may be easily opened for purposes of gaining access to the interior of said housing portion for effecting repairs.

Preferably two series of sources of light are provided in each housing bordered by the cornice members B and C, the series of lamps G directing their rays entirely upon the diffusing members F, and the lamps Q being disposed in the upper portion of said space and equipped with reflectors R for directing rays upon the upper portions of the walls and the ceiling of the auditorium, the relative numbers and candle power of the lamps Q and G being proportioned as desired to illuminate the upper portion of the auditorium with the degree of intensity serving to bring out the decorative features thereof and to aid, to some extent by reflection, the illumination of the lower portion of the auditorium.

It will be obvious, of course, that the brackets D may be shaped as desired to make them convenient to support a person walking on the cornice, and that the housing for the lamps G may be, and preferably are, suitably equipped with a plurality of hinged doors S whereby access to the lamps may be easily had from above.

The reflectors for the lamps Q are preferably so arranged as to reflect the rays from the lamp Q upon the opposite wall of the auditorium, and upon a portion of the ceiling thereof, so that each wall and the contiguous portion of the ceiling will

be illuminated from the opposite side of said auditorium, thereby producing an illumination lacking in shadows which will mar the full effect of the decorative features, especially if the latter are of the relief type very commonly resorted to, and also effecting a very efficient illumination of frescos, paintings, mural decorations, etc., which may constitute the decoration of the walls and ceilings of such auditoriums.

The section F of glass may be disposed end to end to provide an uninterrupted linear light source, but the section may, 15 when the type of cornice used requires it, be separated by opaque elements without suffering diminution of its advantages as the construction and arrangement is easily adapted to all types of moldings and cornices of sufficient cross-sectional dimensions to secure all of the above enumerated advantages.

In the instance illustrated the passageway T behind the cornice and above the side 25 aisles U may be utilized to gain access to the lamps and conduits, the wall A being provided at regular intervals with openings V behind the cornice for this purpose.

The exact location and arrangement of 30 the sources of light will depend, of course, upon the shape of the auditorium, and will depend, to some extent, upon whether the same contains one or more balconies and the extent to which they overhang the floor 35 thereof. Thus the linear sources of light may follow the curvatures of the walls and balcony rails and may be continuous around all, or nearly all, the walls, being omitted from the wall toward which the gaze of the 40 audience is usually directed.

Thus the specific arrangement shown may be changed and modified at will to suit the variations in the conditions met without departing from the invention as defined in 45 the appended claims.

Obviously the intensity of illumination 50 may be varied by providing a plurality of electric circuits or other conduits each feeding alternate lamps or every third lamp in a row so that all, or given fractions of all, lamps may be switched on at will, as indicated in Fig. —4—, particular description being deemed superfluous as this is matter of common knowledge.

55 The present application is a substitute for my abandoned application for Patent Ser. No. 857,788 filed Aug. 20, 1914.

I claim as my invention:

1. In an auditorium, a cornice arranged 60 upon the wall thereof having a continuous longitudinal space therein adapted to contain light-producing elements, conduits and reflectors, and provided with a substantially continuous slot along its lower side through 65 which light can be directed into the lower

part of the auditorium, and a substantially continuous slot along its upper side through which light can be projected into the upper part of the auditorium.

2. In a lighting system for auditoriums, 70 cornices on opposite walls thereof each having a lower and upper substantially continuous slot through which light can be projected into the auditorium, and substantially continuous light-diffusers arranged in 75 the lower slots to prevent direct light rays reaching the lower part of the auditorium.

3. In a lighting system for an auditorium, a cornice arranged on the wall thereof, a substantially continuous slot in 80 the lower part of the cornice through which light can be projected into the lower part of the auditorium, a series of electric lamps within the cornice adapted to project light through said slot, reflectors associated with 85 the lamps to cause a maximum quantity of light to be projected through said slot, a substantially continuous translucent light diffuser in said slot to prevent the direct rays of light reaching the lower part of the 90 auditorium and adapted to spread the rays of light laterally to the slot over the lower part of the auditorium whereby the lower part of the auditorium is substantially uniformly illuminated and shadows are de- 95 stroyed.

4. In a lighting system for an auditorium, a hollow cornice arranged between the floor and ceiling thereof, lighting elements arranged in said hollow cornice, said cornice 100 provided with slots through which the light is projected into the auditorium and reflectors for conserving the light produced by said elements and causing a maximum projection of light through said slots, and 105 a substantially continuous light diffuser in one of said slots for preventing direct light rays entering the auditorium therethrough.

5. In a lighting system of the kind described, for auditoriums, a series of lights 110 within a cornice, a slot through which the rays therefrom can be directed into the lower part of the auditorium, a substantially continuous diffuser closing said slot, a substantially half-closed and continuous 115 housing inclosing said lights, and reflectors within said housing associated with said lights for directing a maximum quantity of light through said diffusers.

6. In a lighting system of the kind described, for auditoriums, a series of lights within a cornice, a slot through which the rays therefrom can be directed into the lower part of the auditorium, a substantially continuous diffuser closing said slot, 125 a substantially half-closed and continuous housing inclosing said lights, reflectors within said housing associated with said lights for projecting a maximum quantity of light through said diffusers and means 130

permitting access to said lamps, reflectors and diffuser from the interior of said cornice.

7. In a lighting system of the kind described for auditoriums, a hollow cornice provided with a substantially continuous slot along its under side, through which light can be projected into the lower part of the auditorium, a substantially continuous diffuser closing said slot and through which light is diffused into the auditorium, said diffuser being hingedly mounted and adapted to be swung into the cornice for cleaning and repairs, and sources of direct and reflected light arranged behind the diffuser.

8. In a lighting system of the kind described, an auditorium provided with a hollow cornice, having a slot along its lower part, a translucent diffuser substantially closing said slot, a substantially closed conduit arranged above said diffuser, the diffuser closing the bottom of said conduit, a series of lighting elements in said conduit, reflectors associated with said lights adapted to project a maximum quantity of light

through said diffuser, normally closed hand-hole openings giving access to said conduit from within the cornice, said diffuser adapted to be swung within the hollow cornice for cleaning and repairing same.

9. A system of indirect uniform illumination for auditoriums, comprising hollow cornices upon opposite walls, substantially continuous slots in the upper and lower sides of said cornices, series of lighting elements within said cornices adapted to direct light through said slots and substantially continuous diffusers in the lower slots preventing the direct light rays reaching the lower part of the auditorium, the light being proportioned, directed and controlled to provide a substantially uniform illumination on substantially the whole interior of the auditorium.

In testimony whereof I have signed my name in presence of two subscribing witnesses.
